UNITED STATES PATENT OFFICE.

RANDOLPH A. WINTERS, OF ATWOOD, KANSAS.

FENCE-WIRE STAPLE.

SPECIFICATION forming part of Letters Patent No. 727,248, dated May 5, 1903.

Application filed March 27, 1902. Serial No. 100,300. (No model.)

To all whom it may concern:

Be it known that I, RANDOLPH A. WINTERS, a citizen of the United States, residing at Atwood, county of Rawlins, and State of Kansas, have invented certain new and useful Improvements in Fence-Wire Staples, of which the following is a specification.

My invention relates to fence-wire staples.

The ordinary fence-wire staple is unsatisfactory, because upon the wood of the post shrinking, which happens after a certain time, the staple drops out or becomes loosened and lets the wires down, necessitating repairing of the fence.

The object of the present invention is the provision of a staple of improved and novel form which will automatically lock when driven and remain in the post until removed by a staple-puller or other suitable means, thereby insuring retention of the fence-wire at all times.

To accomplish the foregoing object, I provide a staple having one leg pointed, so as to drive substantially straight, and the other leg provided with a suitable shear cut on its outside, which acts to cause the leg to bend when driven, thus locking the staple in the post.

In the accompanying drawings, Figure 1 is a sectional view through a fence-post, illustrating my staple driven thereinto and disclosing how the shear-cut leg bends on driving to lock the staple; and Figs. 2 and 3, details of the staple as it appears when furnished for use.

Referring first to Figs. 2 and 3, 1 and 2 designate the respective legs of the staple, which are connected to the arch 3. The leg 1 has a comparatively long shear cut 4 on its outer face, which can be either perfectly straight

or curved, while the leg 2 has an ordinary 40 point 5.

The staple when manufactured and furnished for use appears as shown in Figs. 2 and 3.

Referring now to Fig. 1, it will be seen that 45 when the staple is driven into the fence-post the leg 1 is bent over toward the leg 2. This is caused by the simple act of driving the staple, for the shear cut 4, acting against the wood of the post, is deflected as the staple is 50 driven. The staple is therefore locked by the very act of driving it, and it cannot become loosened or fall out, though it may be withdrawn by the use of a staple-puller.

My staple is primarily intended for use as 55 a fence-wire staple, as it is peculiarly adapted for filling the requirements in that connection.

Having thus described my invention, what I claim as new, and desire to secure by Letters Patent, is—

The herein-described staple comprising two substantially straight legs separated from each other and connected by an arch, one of said legs having a point and constituting a driving-leg adapted to enter the material 65 straight, when driven, and the other leg constituting a locking-leg and having a shear cut in its outer side extending from its tip toward the arch, said locking-leg being adapted to bend toward the driving-leg when the 70 staple is driven and thereby lock the staple.

In testimony whereof I hereunto affix my signature in presence of two witnesses.

RANDOLPH A. WINTERS.
